UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS.

NARROW-WARE-LOOM RACK.

952,159.

Specification of Letters Patent. Patented Mar. 15, 1910.

Application filed July 16, 1908. Serial No. 448,789.

To all whom it may concern:

Be it known that I, WILLIAM WATTIE, a citizen of the United States, residing at Worcester, in the county of Worcester and 5 State of Massachusetts, have invented certain new and useful Improvements in Narrow-Ware-Loom Racks, of which the following is a specification.

My invention relates to narrow ware loom 10 racks, or toothed wooden racks for narrow ware or ribbon looms, which form, either the toothed part of the shuttle, or the toothed rack for operating the shuttles.

The object of my invention is to improve 15 upon the construction of the toothed part of the shuttles, and the toothed shuttle operating racks, referred to, as ordinarily made.

In the ordinary construction of the toothed parts referred to, there is a recessed 20 portion in the shuttle, or in the shuttle operating rack or bar, to receive the toothed part or rack, which is ordinarily made of wood, in one or more pieces, and held in the recess by glue. In this construction of the 25 toothed racks, the separate teeth of the rack are liable to break off.

In my improvements, in addition to the ordinary toothed rack, which fits into and is glued in the recess in the shuttle, or in the 30 recess in the shuttle operating rack, I provide two supplemental toothed strips, corresponding in shape and contour to the toothed racks, one strip for each edge of the toothed rack. Said strips extend within 35 the recess for the toothed rack, at each side thereof, and are glued therein, in a reverse position to the toothed rack, so that the toothed part on the strips will extend downwardly within the recessed portion, with the 40 toothed part extending in the recessed spaces in the rack, and the recessed parts extending over the toothed parts of the rack, so as to cover the ends or edges of the teeth of the rack, and protect the same, and prevent 45 them from breaking off.

I have only shown in the drawing a detached portion of the toothed part of a shuttle, and of a shuttle operating rack, of the class referred to, embodying my 50 improvements, sufficient to enable those skilled in the art to understand the construction and operation of the same.

Referring to the drawings:—Figure 1 is a side view of a detached portion of the 55 toothed part of a circular shuttle. Fig. 2

is a plan view of the toothed part shown in Fig. 1, looking in the direction of arrow *a*, same figure. Fig. 3 is a front view of a detached part of a shuttle operating rack and bar. Fig. 4 is a section, on line 4, 4, Fig. 3, 60 looking in the direction of arrow *b*, same figure. Fig. 5 is a section, on line 5, 5, Fig. 3, looking in the direction of arrow *c*, same figure. Fig. 6 is a side view of a detached part of a supplemental toothed strip. Fig. 65 7 is a side view of a detached part of the toothed rack. Fig. 8 is a side view of a detached part of the rack or rail. Fig. 9 is a side view of the supplemental toothed strip shown in Fig. 6, looking in the direction of arrow *d*, same figure. Fig. 10 is an end view of the toothed rack shown in Fig. 7, 70 looking in the direction of arrow *e*, same figure. Fig. 11 is an end view of the rack bar shown in Fig. 8, looking in the direction of arrow *f*, Fig. 8.

In the accompanying drawing, in Figs. 1, and 2, 1 is a detached part of the runner or base of a circular shuttle, which has a longitudinal recess 1' therein, in the usual way, 80 see Fig. 2. Within the recess 1' extends a toothed rack 2, in the usual way, which is preferably glued therein. In addition to the toothed rack 2 there are two supplemental toothed strips 3, corresponding to the 85 strip 3 shown in Fig. 6. The strips 3 have the toothed portion thereon corresponding to the toothed portions on the rack 2, but each strip 3 is placed within the recess 1' in the strip 1, at each side or edge thereof, in a 90 reverse position to the toothed rack 2, so that the toothed portions on the strips 3 will extend within the spaces between the teeth on the rack 2, and the recessed portions of the strip 3 will extend over the teeth on the 95 rack 2. The supplemental strips 3 are glued within the recessed portion 1' of the bar 1.

In Figs. 3 to 11 inclusive, I have shown my improvements in connection with the toothed rack or bar for operating the shuttles. In said figures, 4 is the rack bar, having a central longitudinal recess 4', see Fig. 11, to receive the toothed rack 2, which is glued within the said recess, and occupies the full width of said recess. 3, Fig. 6, is 105 the supplemental strip. There are two strips 3, see Fig. 4, which extend within the central recess 4' in the bar 4, at each side or edge thereof, and on each edge of the toothed rack 2, in the same manner as above 110

described in connection with Figs. 1, and 2, and are glued within said recess to secure them in place. The supplemental strips 3 are preferably made by sawing strips of the 5 toothed rack 2 up into the narrower strips 3, so that the toothed portions and the recessed portions will correspond exactly, and the supplemental toothed strips 3 will exactly fit onto and over the edges of the 10 toothed rack 2.

The advantages of my improvements will be readily appreciated by those skilled in the art. They are of very simple construction, and may be readily applied to the ordinary 15 rack portion of a shuttle, or to the toothed rack for operating the shuttles. By means of my supplemental toothed strips, the teeth of the rack on the shuttle, or on the rack bar, will be protected, and much less liable 20 to breakage.

It will be understood that the details of construction of my improvements may be varied if desired.

Having thus described my invention, what 25 I claim as new and desire to secure by Letters Patent is:—

1. In racks for narrow ware loom shuttles,

and racks for operating the shuttles, the combination with the toothed portion, of two supplemental toothed strips, to fit onto 30 the rack and cover the side edges thereof.

2. In a narrow ware loom shuttle rack, the combination with the toothed portion, of two supplemental toothed strips, to fit onto 35 the toothed portion, and cover the side edges thereof.

3. In a narrow ware loom shuttle operating rack, the combination with the rack bar, and a rack extending within a recess in said 40 bar, of two supplemental toothed strips extending within said recess and fitting onto the toothed portion of the rack, at the side edges thereof, to cover said edges.

4. An improved shuttle operating rack for narrow ware looms, comprising a bar having 45 a recess therein, a rack extending within said recess, and two supplemental toothed strips extending within said recess, and fitting onto the toothed portion of said rack, at the side edges thereof, to cover said edges.

WILLIAM WATTIE.
